[57] CLAIM

The ornamental design for a toilet bowl brush handle, as shown and described.

DESCRIPTION

FIG. 1 is a rear perspective view of a toilet bowl brush handle embodying my new design.

FIG. 2 is an enlarged top plan view thereof; the bottom plan view being a mirror image.

FIG. 3 is a front elevational view thereof.

FIG. 4 is a rear elevational view thereof.

FIG. 5 is a side elevational view thereof, the opposite side being a mirror image.
